Obeneger & Currier
Obeneger & Currier

The whole referred to in these letters Patent and making part of the same containing a description in the words of the said Obeneger & Currier him self of his improvement in the horizontal square piano forte.

I know ye that I the said Obeneger & Currier, have invented a new and useful improvement in the horizontal square Piano forte, where by each of the harmonies is made to strike one or more of the strings belonging to its proper note at the pleasure of the performer, as is done in the horizontal grand piano forte, and by means of the said invention the following advantages of construction in horizontal piano forte are obtained namely. First, that the key board may be placed exactly mid way of the instrument, which gives the advantage of a compass of seven octaves, and admits of greater beauty & symmetry in the exterior of the instrument. Secondly, the key frame may be supported by a brace, which is secured to the lower frame of the case by bolts, or screws passing through supporters of the brace.

Thirdly, the braces of the instrument may run in the direction of & very near to, the strings, by which means the instrument may be made stronger and lighter & will keep in tune much better than up on the common construction.

Fourthly, it admits of having a larger sounding board than upon the common construction. Which several advantages of construction I also claim as my invention.

And I also hereby declare that the nature of my said invention & the manner in which it is to be made to operate and be carried into effect are fully set forth in the following specification that is to say:

The action, in any piano forte, consists of the following parts: which are arranged and combined as following viz: a stool which holds the hammer and extends from the upper to the lower part, of the case of the piano forte, on the upper side of this stool & at an oblique angle

with its line of vibration is placed a range of levers, which serve the hammer lever, & which with thin springs are inserted in the flanges attached to the back edge of the hammer rail; and these hammer levers correspond to and are connected, as hereinbefore mentioned, with the hammer which are placed on the under side of each hammer rail. The hammer levers project over the jack (which is of the usual construction,) and motion is communicated to the hammer, by connecting rod which passes down from the hammer lever, & is inserted into the end of the hammer socket which are suspended under the rail by flanges with metal pivots.

The hammer may be either parallel with or at a right angle to any other angle with the direction of the strings. Each hammer in its ordinary situation will strike all the strings belonging to its note; but by means of a pedal, which acts upon the hammer end, the whole range of hammers, may be instantly thrown into such a position, that each of them shall strike one or more of its proper strings at pleasure.

The hammer rail is adjusted by means of pivots, which are placed in a line with the ends of the hammer levers, in such a manner that the hammers may be moved, so as to strike the strings in the manner above described without altering the point of contact between the levers & the jacks. The whole construction of the action is such as to prevent the usual recoil of the hammers.

The dampers are placed under the key frame & near the back end of each hammer socket, they damp upon the same side of the string that is struck by the hammer; they also damp at a greater distance from the bridge than is usual in the common construction of piano forte, by which means the damping is more effectual; the dampers are moved by a catch upon the top of their lever, which catch is acted upon by a hook inserted into the under side of the key; the whole of the dampers may be thrown off the strings by means of a pedal.

Now I do further annex to these presents a drawing of my said invention and refer to the same in manner following to wit:

A. A. an end view of the hammer rail with its front plate shown on its side by turning. B. Is the hammer lever, & its spring

of the hammer head, D, the flange of the hammer head, E, the armature rod passing from its pivot C in the hammer box to its pivot E in the end of the hammer socket, F, F, G, the flange of the hammer socket - H, the hammer in its natural position II, the strings, K, one of the two pins on which the hammer can turn in order to move the hammer, so as to strike one or more of the strings at pleasure, L, the damper, M, the damper lever, under the key frame P, N, the damper lever catch on which the hook (O) from the key, acts, O, the hook from the key, acting on the catch of the damper lever, P, the key frame, Q, the damper lever frame, R, R, the ^{top} jack

In testimony that the above is a true specification of my said improvement as above described, I have hereunto set my hand & seal, this second day of April in the year of our Lord one thousand eight hundred and thirty one,

Notary

Joseph Spogue.
